UNITED STATES PATENT OFFICE.

LAROY S. STARRETT, OF ATHOL, MASSACHUSETTS.

DESIGN FOR A MICROMETER-GAGE FRAME.

SPECIFICATION forming part of Design No. 33,784, dated December 18, 1900.

Application filed May 19, 1899. Serial No. 717,505. Term of patent 14 years.

To all whom it may concern:

Be it known that I, LAROY S. STARRETT, of Athol, in the county of Worcester and State of Massachusetts, have invented and produced 5 a new and original Design for a Micrometer-Gage Frame, of which the following is a specification.

In the drawings, Figure 1 is an elevation of a micrometer-gage frame embodying my design; and Fig. 2 is a transverse section on line 10 22, Fig. 1.

My design consists in the new, useful, and original shape or configuration of the article, such shape being distinctly that of a figure 5 15 without the upper terminal line or dash and with a ring D affixed to the convex edge of the

flat body A, near to the straight cylindrical barrel B. Said barrel extends outwardly from one end of said body to a distance considerably greater than the diameter of said ring. An 20 open space of equal extent exists between the ends of the curved body A in the plane of the axis of said barrel.

I claim as my invention—
The design for a micrometer-gage frame, as 25 herein shown and described.

In testimony whereof I have affixed my signature in presence of two witnesses.

LAROY S. STARRETT.
